Filed Oct. 4, 1974, Ser. No. 512,216

Term of patent 14 years

Int. Cl. D10—04

U.S. Cl. D10—57

The figure is a front perspective view of a liquid crystal converter thermometer showing my new design, the rear, not shown, being flat, plain and unornamented.

The rear surface stippling is understood to be continuous and the color shaded diamonds are typical temperature indicators.

I claim:

The ornamental design for a liquid crystal converter thermometer, substantially as shown and described.
